United States Patent Office

Des. 218,962
Patented Oct. 20, 1970

218,962

HANDLE FOR SHOPPING BAG OR THE LIKE

Peter Frederick Hollinworth, Bramhall, Cheshire, England, assignor to Thomas Longworth (Paper) Limited, a corporation of Great Britain

Filed July 22, 1968, Ser. No. 12,850

Claims priority, application Great Britain Feb. 10, 1968

Term of patent 7 years

Int. Cl. D9—99

U.S. Cl. D9—292

FIG. 1 is a plan view of the new handle, the underside being identical with a view shown;

FIG. 2 is a side view of the handle of FIG. 1;

FIG. 3 is a cross section through line 3—3 of FIG. 1;

FIG. 4 is a cross section through line 4—4 of FIG. 1; and

FIG. 5 is a cross section through line 5—5 of FIG. 1.

I claim:

The ornamental design for a handle for shopping bag or the like, as shown and described.
